CLAIM

We claim the ornamental design for sliding door handle, as shown and described.

DESCRIPTION

FIG. 1 is a side elevation view of a sliding door handle showing our new design;

FIG. 2 is a front elevation view of the sliding door handle depicted in FIG. 1, the undisclosed rear is not part of the claimed design;

FIG. 3 is an opposing side elevation view of the sliding door handle depicted in FIG. 1;

FIG. 4 is a top plan view of the sliding door handle depicted in FIG. 1; and,

FIG. 5 is a bottom plan view of the sliding door handle depicted in FIG. 1.

The broken lines are included for the purpose of illustration and form no part of the claimed design.
